BREATHING APPARATUS SUPPLY VALVE

Daniel A. Green, North Braddock Township, Allegheny County, Pa., assignor to Mine Safety Appliances Company, Pittsburgh, Pa.

Application May 31, 1940, Serial No. 337,984

3 Claims. (Cl. 284—19)

This invention relates to a valve arrangement and more particularly to an arrangement which is adaptable in efficiently connecting a breathing apparatus to any one of a series of supply stations incorporated in a manifold connected to a source of respirable air.

It is among the objects of this invention to provide a valve arrangement which is adaptable to connect a breathing apparatus to a manifold air supply, which is compact, simple in operation, low in resistance to movement of air, and inexpensive in construction, which is adaptable to the various systems used in supplying respirable air, which enables rapid engagement and disengagement of an apparatus to a supply system, as may be necessary in connecting or disconnecting breathing apparatus to different stations of a manifold system, and which accomplishes these operations without the loss of any material amount of respirable air from the supply and is operative to seal the inlet of the breathing apparatus during disengagement of the apparatus from the supply system.

In the drawing,

Fig. 1 is a sectional view of a valve arrangement and in which the separable parts are illustrated in a separated position;

Fig. 2 is a sectional view similar to that of Fig. 1 in which the separable parts are illustrated in connected position;

Fig. 3 is a sectional view taken along the line 3—3 of Fig. 1;

Fig. 4 is a sectional view taken along the line 4—4 of Fig. 1;

Fig. 5 is a sectional view taken along the line 5—5 of Fig. 1.

While the invention is being described in connection with the application to a manifold system of distribution of respirable air to a breathing apparatus, it is recognized that the valve arrangement has application to uses other than manifold distribution. However, the valve is especially adaptable to a manifold and it can accommodate adequately pressures which are commonly used in such a means of supply of respirable air. It is operative in such a system to reduce the amount of leakage that ordinarily occurs in connecting the breathing apparatus to an outlet of the manifold and the connection can be made quickly and without much effort. Furthermore, the valve is automatic in closing off the apparatus to the outside atmosphere when the apparatus is disconnected from the supply system.

Referring to the drawing, the valve arrange-

ment illustrated is of two separable parts; the one part 1 forms a part of the manifold, while the other part 1a is connected to the inlet of a breathing apparatus. The part 1 comprises principally a casing 2 in which is provided a central passage 3 and from which an outlet passage 4 leads to define a supply station for a breathing apparatus. This central passage 3 is provided in connecting the casing 2 into a manifold system 10 and the casing is provided with threaded ends which engage coupling members 5 and 6 of the header 8. By this arrangement, the manifold header 8 is connected tightly to the casing 2 and air passing through the manifold passes through the central passage 3 of the casing. A spring loaded and normally closed valve 9 controls the movement of air to the outer passage 4 and is sealed to the casing by cooperation with a gasket 10. A cap 9b is threaded to the casing and seals off an opening 9d through which the valve 9 is inserted and this permits ready replacement or repair of the valve in the event such should be necessary during use of the system. Also, the cap serves to support the spring 9c which acts against the valve and holds it normally closed. As is apparent by comparing Figures 1 and 2, the valve moves in the direction across the central passage 3 in moving the valve to an open position. The valve remains closed until the connectable part 1a defining the inlet of a breathing apparatus or that part which is connected to the inlet of the apparatus is brought into sealed position to the casing. This part 1a is composed of a receiving duct 11 to which is connected an intermediate member 12 which contains a radially directed flange 13 spaced a predetermined distance from the end 11a of the outlet duct 11 which is to engage the valve 10 in moving it into an open position. The flange supports a gasket 23 which engages the end of the casing to provide a fluid tight seal when the duct is moved into the passage 4 sufficiently to open the valve 9.

In order to seal off the breathing apparatus to the atmosphere when the apparatus is disengaged from the supply system, a flexible flutter valve 20 is fastened to the surface of the receiving duct and is held thereto by the pressure of engagement produced by the intermediate member 12. This arrangement of connecting the valve onto the surface of the duct and of the cooperating intermediate member provides a simple method of assembly and also an effective means to seal the valve to the connecting parts. In assembly, the valve is placed on the outer surface of the outlet duct proper and then by assembly of the

intermediate member 12 to the duct, the valve is placed in positive sealing engagement with the duct.

A union or lock holding the parts 1 and 1a in connected position is illustrated as an ordinary bayonet lock 14 in which lugs of part 14a are provided integral with the casing 2 and a hollow nut of part 14b having an integral inward flange composed of separated parts cooperates with the lugs and a recess of part 14a and the two parts may be quickly connected. A small pivoted lever 17 actuated by a spring 18 positioned in a recess in the part 14b locks the nut to the casing proper when brought into engaged position. This is accomplished by the lever 17 engaging the forward side of one of the lugs of part 14a when the inward separated flange engages stops 14c in the recess of part 14a. The gasket 23 is enclosed by the nut of part 14b and it sufficiently engages the end of the casing to tightly seal off the joint when engagement of the two parts 14a and 14b is complete. Also, the end of the duct 11a is moved sufficiently into the passage 4 to move the valve 9 to an open position when joinder of the bayonet lock is completed. All of this depends upon the proper spacing of the flange 13 from the end 11a of the duct 11. Since the end 11a of outlet duct 11 engages the face of the valve 9 when opened, it is necessary to provide inlet openings 24 through which air may pass and as illustrated specifically in Fig. 2. A tube 19 represents the inlet of a breathing apparatus (not shown) and is connected directly to the intermediate member 12.

In the operation of this valve arrangement, the valve 9 being normally closed by a spring 9c closes off the movement of air to the outlet passage 4. When it is desired to connect a breathing apparatus to this station, assuming the outlet 4 to represent one of several like stations or outlets in the manifold 8, the part 1a connected to the breathing apparatus is brought into receiving position by inserting the outlet duct 11 into the passage 4 and then moving it sufficiently inwardly so that the nut of part 14b can be locked into position to the lugs of part 14a by the operation of lever 17 and the parts sealed together by means of the gasket 23. When this is accomplished, the outlet duct will have moved to such a position to force the normally closed valve open and allow the air to move therein and thence to the breathing apparatus after having passed through the rubber valve 20.

If it is desired to move the connection of the breathing apparatus from this station to another similar station, the breathing apparatus can be rapidly disconnected by operation of the lever 17 and by disengagement of separable parts of the lock 14 so that the part 1a is quickly disconnected and by such disconnection the valve 9 closes, sealing off the central passage 3 from the atmosphere. By the operation of the rubber valve 20, the breathing apparatus inlet is sealed from the atmosphere since the rubber valve is operative to allow the passage of air only in one direction, and by my arrangement air is allowed to move only in a direction towards the apparatus from the outlet duct 11. Thus, all of the air contained in the apparatus at the time of disconnection is conserved and by proper design can be made sufficient to supply the user until the apparatus is connected to another station.

It is to be recognized that the pressure differential existing in a supply system to breathing apparatus and especially the pressure differential

existing on the opposite sides of a valve directly controlling the supply to the breathing apparatus may be very small and it is necessary that any arrangement used be operative by small differentials. In addition to fulfilling the essential requirements of the device in controlling an air supply to a breathing apparatus, the whole valve arrangement is compact and positive in action and effective in preventing leakage when the apparatus is engaged or disengaged from a supply system and does not resist to a material extent the movement of air from the source to the apparatus.

It is to be understood that this valve system is directed to controlling the flow of air to breathing apparatus and is especially adaptable in providing a manifold system of supply in which the apparatus can be connected to any one of the series of supply stations provided along a manifold which may be located in a compartment. It is intended that the claims define the scope of this invention.

I claim:

1. In a coupling device to connect a source of respirable air under pressure to a breathing apparatus comprising a housing section adapted to be connected into a manifold arrangement and having a passage therethrough to a connectable outlet, a removable section adapted to be quickly connected and sealed to the connectable outlet of the housing, a normally closed valve in the housing, the removable section having a means engageable with the valve to open the valve when the sections are connected and a duct portion to be attached to an inlet tube of a breathing apparatus, and a low resistance valve sealed to the removable section to control the flow of air in either direction through the duct and positioned within the duct and operative on small differences in pressure on each side of the valve to move from one position to another and effective to seal the breathing apparatus from the atmosphere when the removable section is detached from the housing by the force of pressure in the inlet tube of the breathing apparatus acting on the outer opposite surfaces of the valve.

2. In a coupling device to connect a source of respirable air under pressure to a breathing apparatus comprising a housing section adapted to be connected into a manifold arrangement and having a passage therethrough to a connectable outlet, a hollow removable section adapted to be quickly connected and sealed to the connectable outlet of the housing, a normally closed valve in the housing, the removable section having a means engageable with the valve to open the valve when the sections are connected and having a duct portion to be attached to an inlet tube of a breathing apparatus, and a tubular respiratory flutter valve mounted to and supported by the removable section and positioned within the removable section so that the tubular portion of the valve is arranged to receive the flow of air from the manifold to close off air to the apparatus through the removable section except through the valve and operative to seal the breathing apparatus from the atmosphere when the removable section is detached from the housing by the force of pressure in the inlet tube of the breathing apparatus acting on the outside and opposite surfaces of the valve.

3. In a coupling device to connect a source of respirable air under pressure to a breathing apparatus comprising a housing section adapted to be connected into a manifold arrangement and

having a passage therethrough to a connectable outlet, a removable section adapted to be quickly connected and sealed to the connectable outlet of the housing, a normally closed valve in the housing, the removable section having a means engageable with the valve to open the valve when the sections are connected, a duct attachable to an inlet tube of a breathing apparatus and attachable to an intermediate outside portion of the removable section, the removable section having a cylindrical portion at its outlet end extending within the duct, a tubular rubber flutter valve mounted onto the outer surface of the cylindrical

portion, the duct portion having a surface co-operative with the cylindrical portion to seal the valve material thereto, the tubular flutter valve being positioned in the duct and operative to pass air to the breathing apparatus from the housing section and effective to seal the breathing apparatus from the atmosphere when the removable section is detached from the housing by force of pressure in the inlet tube of the breathing apparatus on the opposite outside surfaces of the valve.
